UNITED STATES PATENT OFFICE

147,549

DESIGN FOR A SLIPPER OR SIMILAR ARTICLE

Denison F. Groves, Evanston, Ill., assignor to Groves Shoe Co., Chicago, Ill., a corporation of Illinois

Application January 10, 1947, Serial No. 136,041

Term of patent 3½ years

(Cl. D7—7)

To all whom it may concern:

Be it known that I, Denison F. Groves, a citizen of the United States, residing in the city of Evanston and State of Illinois, have invented a certain new, original, and ornamental Design for Slipper or Similar Article, of which the following is a specification, reference being had to the accompanying drawing, forming a part thereof.

Fig. 1 is a side elevational view of a slipper showing my new design.

Fig. 2 is a plan view.

Fig. 3 is a front perspective view.

I claim:

The ornamental design for a slipper or similar article, substantially as shown.

DENISON F. GROVES.
